US00D598982S

(12) **United States Design Patent**
Bharaj

(10) **Patent No.:** **US D598,982 S**
(45) **Date of Patent:** **** Aug. 25, 2009**

- (54) **ZONE VALVE ACTUATOR COVER**
- (75) Inventor: **Maninder S. Bharaj**, Scarborough (CA)
- (73) Assignee: **Honeywell International Inc.**, Morristown, NJ (US)
- (**) Term: **14 Years**
- (21) Appl. No.: **29/221,479**
- (22) Filed: **Jan. 14, 2005**
- (51) LOC (9) Cl. **23-01**
- (52) U.S. Cl. **D23/249**
- (58) Field of Classification Search D23/233-237, D23/244-249; 251/59, 30.01, 63.5, 250, 251/337, 129.11, 129.12, 259; 137/556, 137/322; D13/154, 184, 118, 122; 285/328

U.S. Appl. No. 10/802,439, filed Mar. 17, 2004, entitled "Valve for Reducing Water Hammer".

Primary Examiner—Cathron C. Brooks
Assistant Examiner—Maurice Stevens

(57) **CLAIM**

The ornamental design for a zone valve actuator cover, as shown and described.

DESCRIPTION

FIG. 1 is a perspective side view of a zone valve actuator cover;

FIG. 2 is another perspective side view of the zone valve actuator cover of FIG. 1;

FIG. 3 is a perspective overhead view of the zone valve actuator cover of FIG. 1; and,

FIG. 4 is a side elevational view of the zone valve actuator cover of FIG. 1.

The portions illustrated in broken lines on the figures are for illustrative purposes only and form no part of the claimed design.

The broken lines showing unclaimed portions of the zone valve actuator cover form no part of the claimed design.

1 Claim, 4 Drawing Sheets
